ELECTRIC SWITCH MOVEMENT

Filed Jan. 18, 1928

INVENTOR

George Henry Elwell

UNITED STATES PATENT OFFICE

GEORGE HENRY ELWELL, OF NEW HAVEN, CONNECTICUT, ASSIGNOR TO THE GREIST MANUFACTURING COMPANY, OF NEW HAVEN, CONNECTICUT, A CORPORATION OF CONNECTICUT

ELECTRIC SWITCH MOVEMENT

Application filed January 18, 1928. Serial No. 247,630.

The invention relates to improvements in electric switch movements, and more especially to switch movements for electric lamp sockets operated by pull-chains, and the object is to provide for a switch of this character a positive snap action which is identically the same for the opening as for the closing of the circuit.

With this and other objects in view, as will more fully hereinafter appear, the invention consists in certain features of novel construction and arrangement of parts hereinafter described, illustrated in the accompanying drawings and particularly pointed out wherein patentable novelty is claimed for certain features of the device, it being understood that within the scope of what hereinafter thus is claimed various changes in form, proportion, size, adaptability, and minor details of the construction, can be made without departing from the spirit or modifying any of the advantages of the invention.

The following is the description of an embodiment of the invention, reference being had to the accompanying drawings (one sheet) in which Figure 1 is an upright elevation of a portion of the device, partly in cross-section and taken at the line "1-1" of Figure 2; and Figure 2 is an upright elevation of the device at another angle.

Referring more particularly to the drawings, in which similar parts are similarly numbered, the device, while particularly adapted for use in connection with electric lamp sockets, is illustrated in the drawings as a device embodying a sudden closing and opening mechanism for any electrical circuit, the binding-screws 22 and 23 representing opposite poles from which the electrical circuit may be traced to the point of making and breaking. The device is mountable upon a supporting base of insulation 24 and comprises the rocking shaft 1 having fixed thereto the operating arm 2 from which is suspended the pull-chain 3 as a convenient method of operating the switch movement, as illustrated by the Figure 1. Mounted upon the shaft 1 are the conductive disk 4, properly insulated therefrom, and the non-

conductive disk 5, together relatively rotatable thereon with a limited laterally sliding movement upon the shaft. The conductive disk 4 is peripherally provided with a ratchet formation 6 having abrupt shoulders 7 and also having spaced laterally disposed lugs 8 providing conductive shoulders as illustrated by the Figure 1. The non-conductive disk 5 is provided with similar lugs 9 which are so bent around the periphery of the ratchet formed disk 4 at places of mean diameter that the disk 5 is thereby rotatably carried by the disk 4 and the lugs of both disks together provide alternately spaced conductive and non-conductive shoulders lying in the same plane parallel with that of the disks for a purpose to be explained, as illustrated by the Figures 1 and 2. Permanently engaging the ratchet periphery of the disk 4 is a conductive resilient pawl 10 electrically included within the circuit, as illustrated by the Figure 2, and adapted to operate with the abrupt shoulders 7 to positively prevent any forward rotatable movement of the united disks 4 and 5. The arm 2 is provided with the rigid catch member 11 adapted to engage the adjacent one of the abrupt shoulders 7 to backwardly rotate the united disks 4 and 5 one step under pawl 10. Anchored to the conductive sleeve 12 and the sleeve of insulation 13, both of which are fixedly carried by the shaft 1, is the conductive coiled spring 14 insulated from the shaft 2 and the disk 4 by means of the sleeve of insulation 13 and the washer of insulation 15, and having a free end 16 adapted to engage behind the adjacent one of the shoulders 8 and 9 to there exert a forwardly tension. The coiled spring 14 also functions as a compression spring to maintain the united disks 4 and 5 snugly against arm 2, but permits these united disks to yield against the spring tension when the rigid catch is backed away from its engaging position behind one of the abrupt shoulders 7 to engage the next forwardly located shoulder 7. Mounted upon the shaft 1 adjacent the arm 2 is a second coiled spring 17 having one end fixed, as at 18, to the base and the other end secured, as at 19, to the arm 2 for the purpose of provid-

ing merely an automatic spring actuated return of the forwardly operated arm 2, the movement of the arm 2 being limited in both directions by the stops 20 and 21, illustrated 5 by the Figure 1, which in connection with an electric lamp socket might be provided by the limits within a casing slot within which the arm may operate.

From the foregoing description the operation 10 of the device will be obvious. The arm 2 being operated forwardly by means of a downward pull of the chain 3, the shaft 1 is rocked forwardly bodily carrying with it the conductive spring 14, the free end 16 of that 15 spring being detained behind the adjacent non-conductive shoulder 9 until the final limited movement of the shaft 1 winds the spring 14 and thus shortens the free end 16 to an extent that causes it to slip with a snap 20 from behind that shoulder and then lengthen out to engage behind the next adjacent conductive shoulder 8 by which engagement the circuit is closed. The next following pull of the chain 3 repeats the operation, but causes 25 the free end 16 to snap from behind the adjacent conductive shoulder to engage behind the next shoulder which is one of the non-conductive shoulders 9 by which engagement the circuit is opened. With each forward 30 movement of the arm 2 the rigid catch member 11 by its cam action throws off laterally the united disks 4 and 5 sufficiently for the rigid catch member to pass a section of the ratchet formation of the detained disk 4 to 35 engage the next forward abrupt shoulder 7, and with each automatic backward return of the arm 2 the rigid catch 11, thus interlocked with that abrupt shoulder 7, carries therewith the united disks 4 and 5 one step under 40 pawl 10. With a closed circuit the conductive line of electrical connection may be traced from the binding-screw 22 through the post, the conductive sleeve 12, the spring 14, the spring end 16, one of the conductive shoulders 45 8, the conductive disk 4, the pawl 10, and to the binding-screw 23 through the post to which the pawl 10 is secured. In connection with an electric lamp socket the device might retain the binding-post having the binding- 50 screw 22, but the post having the binding-screw 23 might have in place of the screw an electrical connection with the usual screw-shell or center contact.

What I claim is:—

55 1. An electric switch movement comprising a rocker shaft adapted to be mounted upon a supporting base; two disks, one within the electrical circuit and insulated from the shaft upon which both disks are relatively rotatable and movable in a backward direction only and together presenting alternately spaced conductive and non-conductive shoulders; a spring member anchored to the shaft but insulated from the shaft and the conductive 60 disk, the member extremity being adapted 65

to exert a forward tension against the adjacent one of the shoulders; means adapted to rock the shaft, and hence the spring member, forwardly to cause the spring extremity to snap forwardly from one to the next of the shoulders to close or open the circuit, and means carried by said rocking means to carry the disks backwardly one step upon the backward movement of the shaft. 70

2. An electric switch movement comprising 75 a rocker shaft adapted to be mounted upon a supporting base; two disks, one insulated from the shaft and both relatively rotatable upon the shaft and together presenting alternately spaced conductive and non-conductive shoulders; a spring member within the electrical circuit and carried upon the shaft but insulated from the shaft and the conductive disk, its free end adapted to exert a forward tension against the adjacent one of the shoulders; conducting means in electrical connection with the conductive shoulders and adapted to positively prevent the forward movement of the disks; manual operating means adapted to rock the shaft forwardly to cause 80 the spring end to snap forwardly from one to the next of the shoulders to close or open the circuit; and means carried by the operating means to move the disks backwardly one step upon the backward movement of the shaft. 85

3. An electric switch movement comprising 90 a rocker shaft adapted to be mounted upon a supporting base and having a fixed operating arm; two spring members mounted 95 upon the shaft, one end of one spring being adapted to be fixed to a base and the other spring being within the electrical circuit and bodily carried by but insulated from the shaft, and the free ends of both springs exerting 100 opposing backward and forward tension, respectively, upon the arm and upon rotatable disks, both relatively movable upon but one insulated from the shaft and together presenting alternately spaced conductive and 105 non-conductive engaging shoulders; conducting means permanently in electrical connection with the conductive disk and adapted to positively prevent any forward movement thereof; and a connection between the arm 110 and the disks adapting the arm to carry the disks backwardly, the operating arm having a limited movement for rocking the shaft and thereby causing the shoulder-engaging end 115 of the bodily carried spring member to snap 120 forwardly from one to the next of the engaging shoulders to close or open the circuit, the return movement of the operating arm being urged by the backwardly exerted spring tension to automatically carry the disks backwardly one step. 125

4. An electric switch movement comprising 130 a rocker shaft adapted to be mounted upon a supporting base of insulation and having a fixed operating arm; a conductive disk

relatively rotatable upon but insulated from the shaft and having peripheral ratchet formation and laterally disposed spaced shoulders; a non-conductive disk mounted upon
5 the shaft and carried by the conductive disk by means of shoulders extending from the former around the latter at places of mean diameter and thereby maintained in the same plane parallel to the disks as that of the conductive shoulders, the disks together presenting alternately spaced conductive and non-conductive shoulders; two spring members mounted on the shaft, one on either side of the disks and the arm, one end of one spring
10 being adapted to be fixed to a base and the other spring being conductive within the electrical circuit and anchored to the shaft but insulated from the shaft and the conductive disk, the free ends of both springs exerting
15 opposing backward and forward tension, respectively, upon the arm and upon the adjacent one of the shoulders; a resilient conducting means permanently in electrical connection with the ratchet formation of the conductive disk and adapted to positively prevent any forward movement thereof; and a rigid catch member provided by the arm and adapted to engage the ratchet to rotate the disks backwardly one step, the forward movement of the arm causing the shoulder-engaging end of the conductive spring to snap forwardly from its retarded position behind one to the next of the engaging shoulders to close or open the circuit.
